UNITED STATES PATENT OFFICE.

DAVID S. ANTHONY, OF SIOUX CITY, IOWA.

HORSESHOE.

1,174,796.

Specification of Letters Patent.

Patented Mar. 7, 1916.

Application filed June 17, 1914. Serial No. 845,589.

To all whom it may concern:

Be it known that I, DAVID S. ANTHONY, a citizen of the United States, and a resident of Sioux City, in the county of Woodbury and State of Iowa, have invented a new and Improved Horseshoe, of which the following is a full, clear, and exact description.

This invention relates to shoes of that type having removable calks, but more particularly to a horseshoe of that character in which the calks are carried by a plate or removable section which is fitted to and detachably fastened on the main or body portion of the shoe.

The general objects of the invention are to improve and simplify the construction of sectional horseshoes of the character referred to so as to be reliable and efficient in use, comparatively inexpensive to manufacture, and so designed that the calk-carrying section or plate can be easily and quickly removed without any special tools, and that the calk-carrying plate will firmly fit the body section of the shoe when fastened thereto, without there being any play or rattling between the parts.

More specifically, the objects of the invention are to provide a shoe in which the body section has on its under face a channel, or is otherwise formed to receive the calk-carrying section which has novel means for interlocking with the heel portions of the body section and which at the toe portion has novel means coöperating with the corresponding portion of the body section, whereby a single pin or key serves to detachably lock the sections of the shoe, such pin being easily inserted and removed, yet incapable of accidental detachment.

With such objects in view, and others which will appear as the description proceeds, the invention comprises various novel features of construction and arrangement of parts which will be set forth with particularity in the following description and claims appended hereto.

In the accompanying drawings, which illustrate certain embodiments of the invention, and wherein similar characters of reference indicate corresponding parts in all the views, Figure 1 is a perspective view of the shoe with half of the body section removed and with a portion of the calk-carrying section broken away so as to bet-

ter illustrate the details of construction; Fig. 2 is a bottom plan view of the body section; Fig. 3 is a bottom plan view of the calk-carrying section; Figs. 4, 5 and 6 are sectional views through the shoe when the two parts thereof are fastened together, the sections being taken respectively on the line 4—4, 5—5 and 6—6, Fig. 2; Fig. 7 is a bottom plan view of the toe portion of a modified form of shoe; Fig. 8 is a sectional view on the line 8—8 of Fig. 7; Fig. 9 is a side view of a modified form of calk-carrying plate wherein the calks are blunt, as distinguished from the sharpened calks shown in the other figures; Fig. 10 is a sectional view of the toe portion of a modified construction, showing the locking in front of the calk; and Fig. 11 is a sectional view on line 11—11, Fig. 10.

Referring to the drawing, A designates the body section or top plate of the shoe, and B the calk-carrying section or bottom plate. The body section A in its general outlines is the same as an ordinary shoe and is provided along its sides with rows of openings 1 for receiving the nails whereby the shoe is fastened to the hoof of a horse. The under side of the body section is provided with a channel 2 which extends from one heel 2 to the toe portion 3, and thence to the other heel 2^a, such channel being bordered on its outside by a flange 4 which lies between the channel and the marginal portions that have the nail-receiving openings, such flange 4 being extended forwardly at 5 so as to be flush with the front surface of the toe, and also so as to expand and enlarge the front part of the channel. The inner wall of the channel is formed by a flange 6 which conforms in shape to or follows the inner edge of the shoe. The ends of the channel terminate slightly inwardly from the end edges of the heels, and these channels open upwardly in the top surface of the body A. The side walls 7 of the ends of the channel converge upwardly toward the opening 8 so as to provide a wedging fit with the hooks 9 on the calk-carrying sections, said hooks being adapted to engage the bar portions 10 closing the rear sides of the openings 8.

The body section A at the toe has its under surface shaped concave at the portion 11 so as to receive the convex or raised part 12 on the top portion of the calk-carrying sec-

tion. Depending from the center of the shallow socket or convex portion 11 is a lug 13 which has an opening 14 extending from side to side or in a direction approximately parallel with the front edge of the toe. The body portion as thus described is made in one piece and is preferably, although not necessarily, a die casting. The removable section B which carries the calks is shaped 10 to conform the channel in the under side of the body section, in which channel it fits; that is to say, the side members 15 enter the side portions of the channel a, while the front or toe portion 16 of the section B is 15 horizontally enlarged to fit into the enlarged front portion of the channel a. This enlarged front portion 16 is concave on its under side and convex on its upper side so as to snugly fit in the cavity in the body section of the shoe, and the portion 16 has a 20 central opening 17 into which the lug 13 is adapted to extend downwardly.

By making the toe portions of the two sections comparatively thin and nested one in 25 the other, the lug 13 may be made so short that it will not project down below the bottom of the shoe, and hence will not be subjected to wear; and furthermore, the cavity or chamber provided in the bottom of the 30 toe portion of the section B enables the locking pin or key 18 to be accommodated, such pin being passed through the opening 14 in the lug 13 and having its ends extending out of the lug so as to engage the section B 35 and lock the same to the section A. This pin has a head or shoulder 20 and tapers therefrom to the point 21, and one side of the pin can be provided with serrations or corrugations 22, so that when the pin is driven into 40 place by a hammer, one of the corrugations will finally fit or engage with the lug 13 and prevent accidental detachment of the pin, which latter is springy or yielding.

In attaching the calk-carrying section to 45 the body section of the shoe the hooks 9 are first engaged in the openings 8 in the heel portions of the body section, it being necessary to hold the calk-carrying section at an angle to the other section during the insertion 50 of the hooks 9, and after the hooks are inserted the calk-carrying section is brought upwardly and entered into the channel of the body section A, whereby the apertured lug 13 enters the opening 17. The pin 18 is 55 then driven through the lug whereby the two parts of the shoe are locked together. It will be observed that the base or inner portions of the hooks 9^a are wedge-shaped so as to wedge into the correspondingly 60 shaped ends of the channel a in the heels, such wedging action being clearly shown in Fig. 6. It will thus be seen that the heel portions of the two sections will be effectively clamped together without any lateral 65 play and without the possibility of rattling,

and the toe portions of the two sections will be tightly clamped together by the wedge-shaped pin 18. The calks b and b' at the toe and heels are shown as of the sharpened type in Figs. 1, 3 and 4, but it is obvious that the 70 calks b², b³, may be blunt, as shown in Fig. 9. In other words, the calk-carrying plates can be made in different forms and used interchangeably, according to the road conditions. 75

In Figs. 7 and 8 a modified form of connecting means between the toe portions of the shoe sections is shown. The concave part of the toe is provided with a pair of parallel bars or apertured lugs 32 that are spaced apart to receive between them an 80 apertured lug or arched bar 23, so that a locking pin 24 can be inserted through the said lugs, the apertures of which register, there being openings 25 in the toe portion of the heel-carrying section so as to permit the key or pin 24 to be inserted and driven home. By reason of the concave surface in the under side of the toe portion of the calk-carrying section, the key will be bent as it 85 is driven, so that there is no possibility of its 90 automatic detachment.

In the arrangement shown in Figs. 10 and 11, the locking pin 30 is located in front of the calk 31. The under side of the front portion of the body section A' is cut out to 95 form a shallow socket 32 which provides an opening 33. Extending across this opening from the front to the rear is a depending loop or apertured lug 34 to receive the pin 30. The calk-carrying section B' has a ball 100 portion 35 which fits in the socket 32, and at the center of the ball portion 35 is an opening 36 to receive the lug or loop 34. The under side of this ball portion 35 is cut out 105 shallow to form a chamber 37 to accommodate the locking pin 30 when driven home into the lug 34, such pin frictionally engaging the surface of the chamber 37 so that the pin will remain fixedly in place.

From the foregoing description taken in 110 connection with the accompanying drawings, the advantages of the construction and method of operation will be readily understood by those skilled in the art to which the invention appertains, and while I have described the principle of operation, together with the device which I now consider to be the best embodiment thereof, I desire to have it understood that the device shown is 115 merely illustrative, and that such changes 120 may be made when desired as are within the scope of the appended claims.

Having thus described my invention, I claim as new and desire to secure by Letters Patent:

1. A horseshoe comprising a body section, 125 an apertured lug depending from the toe portion of the said section, a bottom section having a toe calk and an opening out of the plane of the calk to receive the lug, and 130

a locking pin inserted through the lug and disposed in front of the toe calk for fastening the sections together.

2. A horseshoe comprising a body section, 5 an apertured lug depending from the toe portion of the said section, a bottom section having a toe calk and provided with a cavity in its under side and an opening in the cavity to receive the lug, and a locking pin passing through the lug and lying 10 within the said cavity for locking the sections together, the top surface of the cavity being sloping from the opening in opposite directions, and the locking pin being 15 engaged with such surface.

3. A horseshoe comprising a top or body section, a depending lug on the under side thereof, a calk carrying section having an opening to receive the lug, said lug being 20 of such length that its lower end lies above the bottom surface of the calk carrying section, and a device removably engaged with the lug to lock the sections together and extending substantially parallel with the 25 length of the calk on the calk-carrying section.

4. A horseshoe comprising a top or body section, a bottom, calk carrying sections, means for connecting the heel portions of 30 the sections together, the toe portion of body section having a cavity on its under side, an apertured lug extending downwardly in the said cavity, the toe portion of the bottom section being shaped to enter the cavity of the body section and having 35 an opening to receive the lug, and a key inserted through the aperture of the lug and located behind and substantially parallel with the calk for holding the sections 40 of the shoe together.

5. A horseshoe comprising a top or body section, a bottom, calk carrying sections, means for connecting the heel portions of

the sections together, the toe portion of body section having a cavity on its under side, 45 an apertured lug extending downwardly in the said cavity, the toe portion of the bottom section being shaped to enter the cavity of the body section and having an opening to receive the lug, a toe calk disposed on 50 the bottom section forwardly of the said opening, and a key inserted through the aperture of the lug and located behind and substantially parallel with the calk for holding the sections of the shoe together. 55

6. A horseshoe comprising a body section having a channel in its under surface extending from one heel to the toe and therefrom to the other heel, there being 60 openings in the ends of the channel at the heels, a lug in the channel at the toe, a calk-carrying section shaped to fit in the channel and having an opening to receive the lug, and hooks on the heel portions of 65 the calk-carrying section for engaging in the openings in the heel portions of the body section.

7. A horseshoe comprising a body section having channeled heel portions provided 70 with openings, the sides of the channel being inclined inwardly toward each other, a calk carrying section, means for connecting the sections together, said means comprising hooks on the latter for engaging in the openings of the body section, the base 75 portions of the hooks having sloping sides to wedge into the channel, and additional means for fastening the sections together.

In testimony whereof I have signed my name to this specification in the presence of 80 two subscribing witnesses.

DAVID S. ANTHONY.
